UNITED STATES PATENT OFFICE

2,506,315

MAGNETIC DRIVE FOR TEXTILE MACHINES

Anker Petersen, South Boston, Mass., assignor to
Petersen Braiding Machine Company, a copart-
nership

Application October 10, 1947, Serial No. 779,186

8 Claims. (Cl. 87—44)

1

This invention pertains to drive means for imparting movement to a bobbin carrier and is useful, for example, in weaving looms, braiding machines or in fact in any machine wherein a thread-carrying bobbin or shuttle must be moved along a predetermined path. As here illustrated, by way of example but without limitation as to its use, it is shown as embodied in a braiding machine of the general type wherein one set of bobbin carriers (hereinafter for convenience referred to as the "inner set") is revolved in an annular path about the axis of the machine, while a second set of bobbins or bobbin carriers (hereinafter referred to for convenience as the "outer set"), disposed in a circle concentric with the axis of the machine, either revolves in a direction opposite to the carriers of the inner set or remains stationary. The strands from the bobbins of the outer set are so controlled that each carrier of the inner set passes alternately over and under strands from the outer set. A machine of this general type is shown in the patent to Anker Petersen, No. 1,796,938, granted March 17, 1931, for example. In the patented construction the carriers of the inner set are moved along their circular path by means of drive rolls which are bodily revolved in a path concentric with that in which the carriers move, the peripheries of these drive rolls engaging the peripheries of complementary driven rolls mounted on the carriers. With this arrangement the strands of the carriers or bobbins of the outer set pass between the contacting peripheries of the driving and driven rolls without substantial difficulty, thus lessening the danger of injury to the strands as compared with the results of the use of other and prior types of drive. However, for the most effective operation of such roll drive, it is necessary to rotate the drive rolls on their own axes as they revolve in their operative path; the provision of means for thus rotating these drive rolls adds to the cost of machine manufacture and upkeep, and wear of the parts after long use may result in lost motion with consequent lag at starting and over-run in stopping. The patent to Earl Petersen, No. 2,177,742, dated October 31, 1939, discloses an arrangement wherein a magnetic drive is substituted for the mechanical roll-drive of the aforesaid Anker Petersen patent, and the use of this magnetic drive completely eliminates all possibility of abrasion of the strands from the outer set of carriers due to the action of the driving means; it reduces the cost of machine manufacture and maintenance and also reduces noise and vibration.

2

The present invention constitutes an improvement upon the magnetic drive of the Earl Petersen patent. The principal object of the present invention is to provide a magnetic drive for braiding machine carriers or the like which will be powerful enough to drive the braiding carrier at a very high speed, even though the carrier be of a size to support a bobbin of large capacity and which is also effective to start the carrier into operation without appreciable lag when the machine starts, and to stop the carrier without overtravel when the machine is stopped. A further object is to provide a magnetic drive for a carrier of a braiding machine or the like which affords a magnetic field of substantial area, for example, a field which extends over substantially the entire circumferential width of the carrier but which is created by means which does not interfere with the bobbin or restrict the permissible size of the latter, and without necessitating any undesirable location of the bobbin upon the carrier. A further object is to provide a magnetic drive for a braiding machine carrier or the like so devised that ample magnetic driving force for each carrier is attained by the use of a single magnet in cooperation with a soft iron armature or armatures mounted on the carrier. Other and further objects and advantages of the invention will be pointed out in the following more detailed description and by reference to the accompanying drawings wherein

Fig. 1 is a vertical diametrical section, partly broken away and with parts omitted, showing the head of a braiding machine embodying the present invention;

Fig. 2 is a fragmentary plan view, with parts omitted, of the machine shown in Fig. 1;

Fig. 3 is a fragmentary side elevation, to larger scale, of the upper part of the machine shown in Fig. 1 and with many parts omitted and parts in section, showing one of the braiding carriers and the means for driving it;

Fig. 4 is a plan view of the supporting ring on which the driving magnets are mounted;

Fig. 5 is a bottom view, partly broken away, of one of the carriers for a bobbin of the inner series;

Fig. 6 is a fragmentary perspective view, to larger scale than Fig. 5, partly in vertical section, showing the bottom plate of the carrier and the armature bars mounted therein; and

Fig. 7 is a perspective view, to larger scale, illustrating a desirable form of drive magnet.

Referring to the drawings, the frame of the machine is shown as comprising a spider having

arms 20 which radiate from the base (not shown) of the machine, these arms supporting the annulus 22 having a seat for the cam ring 23 provided with the cam groove 24 on its inner face. The base of the machine also carries the fixed hollow shaft 25 which supports the braiding die D having a central aperture defining the braiding point. A sleeve 26 turns on the shaft 25, the lower end of the sleeve 26 preferably resting upon an anti-friction step bearing (not shown) carried by the base. Any suitable type of anti-friction bearing 27 is interposed between the hollow shaft 25 and the sleeve 26 near the upper end of the latter. The hub 28 of a spider device is splined to the sleeve 26 and this spider device carries an annular gear 29 which meshes with a pinion 30 on a drive shaft 31. The hub 28 supports the inner race 32 of a ball bearing while the outer race 33 of this bearing supports a ring member 34 to which an annular gear 35 is secured. This gear 35 meshes with the pinion 30 which thus drives the gears 29 and 35 in opposite directions.

The ring 34 supports a plurality of spaced arms 36 which carry an annulus 37 concentric with and spaced inwardly from the cam ring 23. A second ring member 38 is secured to the upper edge of the ring 37 or it may be integral therewith if desired, and this member 38 carries inwardly projecting arms 39 connected by a circumferentially extending ring 40. Downwardly directed arms 41 extend from the ring 40 and at their lower ends support a guide ring 42, concentric with the ring 37. The opposed faces of rings 37 and 42 are provided with grooves 43 and 44, respectively, constituting guideways for the inner series of bobbin carriers hereinafter more fully described. Each of the grooves 43 and 44 has spaced upper and lower walls which are normally circumferentially continuous so that when a carrier has once been engaged with these grooves it is held positively in position and, while free to move circumferentially, is constrained against substantial axial movement. As some suitable point, either in the ring 37 or the ring 42, a removable section (not shown) is provided to permit insertion and removal of the carriers when desired.

A hub member 45 is secured to the upper part of the sleeve 26 and carries a plate 46 which supports a ring 47 which constitutes a support or carrier for the drive magnets 48. There are as many of these drive magnets as there are carriers of the inner series. Four such magnets are here illustrated (Fig. 4). These magnets (Fig. 7) are preferably of U or horseshoe shape, each having the south and north poles S and N, respectively. These magnets are permanent magnets of the high flux-density type now available, such magnets having a magnetic life of long duration.

These magnets 48 are of substantial length for example three inches or more, and each is arranged with its long dimension substantially perpendicular to a radius of the supporting ring 47. Preferably the upper surfaces of the poles of these magnets are flush with the upper surface of the ring 47, although they may project upwardly beyond said surface if desired. These magnets are secured in openings in the ring 47 in any desired way, for example, by a press fit. The rings 47 are of a non-magnetic material, for example aluminum. Preferably, the length of each magnet approximates the circumferential width of one of the carriers of the inner series, and is desirably at least as long as the bobbin or spool which is mounted on the carrier. Preferably, the pole pieces of these magnets are shaped to pro-

vide a series of spaced ribs 49. As here illustrated, each pole piece has six of these ribs, corresponding ribs of the two pole pieces being aligned with each other. These ribs produce zones of intense magnetic flux.

The ring 40 forms a convenient support for a series of brackets 53 (in number corresponding to the number of bobbin carriers of the inner series) which are attached to the ring in any suitable manner and spaced at regular intervals circumferentially of the ring. These brackets support the bobbins 54 of one series which, for convenience, is here referred to as the "outer" series, the brackets 53 being referred to as the bobbin "carriers" of the outer series. These brackets 53 are of sufficient height to accommodate rotating bobbins 54 of the desired diameter.

A warp lever is associated with each of the brackets 53. A bracket 61 (Figs. 1 and 2) is secured to the outer surface of the ring 37 at a point corresponding to the location of each bracket 53, each bracket 61 comprising a spacer member 62 having a recess 63 at its inner side for the reception of a part of the warp lever. The member 62 is provided with a pivot pin 65 about which the warp lever swings. The warp lever shown comprises a substantially rigid base portion consisting of two elongate strips 66 and 67 (Fig. 2) of sheet metal spaced apart at one end to straddle over the spacer member 62 and having aligned journal openings for the pivot pin 65, one of these members 61 having its pivoted end disposed in the recess 63 and the other engaging the other surface of the part 62. The ends of these parts 66 and 67 may, if desired, be welded to the pivot pin 65. The members 66 and 67 converge and are united at their other ends by means of a pin 68 which constitutes a pivot for an anti-friction cam follower 69 which engages the cam slot 24 in the annulus 23. The warp lever is extended beyond the pin 68, as shown at 72 (Fig. 2), and the free portion of the lever is curved substantially concentrically with the cam ring 23 and at its end is furnished with a thread guide aperture or eye which is disposed radially opposite to a vertical slot 74 (Fig. 1) in the ring 37. The yarn Y from the bobbin 54 passes down through an elongate guide eye in a bracket 75 secured to the ring member 38 and thence through the hook end 76 of a detector and thence down through a guide coaxial with the pivot pin 65 and thence lengthwise of the warp lever and through the guide eye at the end of the latter, and thence inwardly beneath the ring 42 to the braiding point defined by the die D.

The bobbins 54 of the inner series are journaled in suitable bearings in bobbin carriers 82 (Figs. 2, 3 and 5). Each of these bobbin carriers 82 comprises a rigid frame made as light as possible, consistent with strength and rigidity, for example, from aluminum or magnesium or some alloy of these metals. Each bobbin carrier is provided with supporting elements, here shown as anti-friction rolls 83 and 84 at its outer edge, which engage the guideway 43 in the ring 37. At its inner edge each carrier is provided with a supporting element, here shown as a roller 85, which engages the guideway 44. Preferably, the rolls 83, 84 and 85 have anti-friction bearings.

Each of the carriers 82 is provided with a bottom plate 90 (Figs. 5 and 6) which may be integral with the carrier frame or which, as here illustrated, is an independent part secured to the underside of the frame by screws, bolts, welding or brazing. This bottom plate 90 is ar-

ranged below the horizontal plane which is tangent to the maximum diameter of the bobbin 81, so that the plate does not in any way interfere with the free rotation of the bobbin. As illustrated, this plate 80 is elongate in the direction of travel of the carrier, extending across the entire width of the carrier and is at least as long as the maximum length of one of the magnets 48. The plate 80 supports a series of spaced, parallel armature bars 91 of soft iron. These bars are preferably set into the substance of the plate 80 so as to be flush with the lower surface of the latter. As shown in Fig. 6, these bars 91 are provided on their opposite edges with grooves 93 and are thus interlocked with the material of the plate 80. The plate 80 may be a casting of aluminum, magnesium or other non-magnetic material, and the bars 91 may be cast into the substance of the supporting plate. However, it is contemplated that the bars 91 may be secured in other desired manner to the plate 80. For example, the latter may be of sheet material, and the bars 91 may be attached to it by flanges of the sheet material or by rivets or the like. The armature bars 91 are spaced apart equal distances and by the same amount as the ribs 49 of the pole pieces of the magnets 48 so that one of the bars 91 is normally registered with each of the ribs 49. The bars 91 are of a length (radially of the path of the carrier) substantially equaling the transverse thickness of the magnet, each of the armature bars 91 being disposed directly above and very close to one of the ribs of the magnet. While single magnets 48 are here illustrated, and while each carrier 82 is shown as provided with a single row of armature bars, it is obvious that if additional driving force be desired, as, for example, when the yarn masses on the carriers are very large, two or more of the magnets 48 may be arranged as a group, the several magnets of a group being at different distances from the center of the machine, and corresponding rows of armature bars being similarly arranged.

With this arrangement, there is no mechanical driving connection between the rotating ring 47 and the carriers 82, but by reason of the intense magnetic flux in the vicinity of the ribs 49 of the magnets, the size of the magnets and the number of armature bars 91, the latter are held firmly by magnetic attraction in definite registry with the magnet ribs, and the rotation of the ring 47 thus drives the carriers 82 at the same speed as the ring 47. The magnetic force is so great that in starting the machine there is no appreciable lag of the carriers 82 with respect to the ring 47, and in stopping there is no over-travel of the carriers. This form of drive permits the yarn Y from the bobbins of the outer series to pass freely under the carriers 82 without contact with any mechanical part which would subject them to abrasion, substantial compression or retarding force, and thus by the use of this drive, yarn breakage, as compared with that which occurs in machines of the customary type, is very greatly reduced and in fact substantially eliminated. With this drive it is possible to braid yarns which are very tender and fragile and to drive the machine at very great speeds without substantial danger of breakage of yarn.

By the use of the single elongate magnets 48 and armature bars herein disclosed it is possible to obtain sufficient magnetic driving force, thus avoiding the necessity of mounting magnets on the carriers. The series of narrow armature bars

91 weighs substantially less than a magnet, and thus the weight of the carrier is very substantially reduced as compared with an arrangement in which opposed magnets are mounted on the carrier and driving ring, respectively. Moreover, the armature bars 91 may be so narrow, vertically, as to occupy but little space, and thus the row may be extended across the entire width of the carrier without interfering with the free rotation of the bobbin or imposing any limits upon the diameter of the bobbin. As above suggested, more than one series of armature bars may be used on the same carrier, the several series, for example, extending across the entire width of the carrier in a radial direction. It is thus possible to increase the magnetic driving force very substantially as compared with previous constructions in which magnets are mounted on the carrier itself, but without reducing the size of the bobbin or unduly increasing the weight of the carrier.

While a desirable embodiment of the invention has here been described by way of example, it is to be understood that the invention is broadly 25 inclusive of any modifications falling within the scope of the appended claims.

I claim:

1. In a textile machine, in combination, a bobbin carrier, means for guiding it to move in a predetermined path, a permanent magnet of unitary construction having a pole piece which is elongate in the direction of travel of said carrier, said pole piece being divided lengthwise into a plurality of spaced pairs of poles affording 30 spaced zones of intense magnetic flux means for moving the magnet in a path parallel to that of the carrier with its pole piece closely adjacent to the carrier, and a plurality of narrow, parallel spaced armatures corresponding in number to the pairs of poles fixed to the carrier, the outermost 35 of said armatures being spaced from each other a distance substantially equaling the effective length of said magnet pole piece.

2. In a textile machine, in combination, a bobbin carrier, means for guiding it to move in a predetermined path, a permanent magnet of unitary construction having a pole piece which is elongate in the direction of travel of the carrier, said pole piece being divided into a series of 45 parallel spaced ribs providing a magnetic field having spaced zones of high magnetic flux, and a series of parallel armatures, in number equaling the number of magnet pole ribs, said armatures being fixed to the carrier and being spaced apart 50 so that each armature cooperates with one of the ribs of the magnet pole piece.

3. In a circular loom textile machine, in combination, a bobbin carrier, means for guiding it to move in a predetermined path, a plurality of permanent U-shaped magnets of unitary construction having pole pieces which are elongate in the direction of travel of the carrier, each pole piece being divided into a series of parallel ribs thereby to provide spaced pairs of poles affording 55 a magnetic field having spaced zones of high magnetic flux, and a series of narrow, parallel armatures fixed to the carrier, each armature being of a length to extend across both poles of the magnet, the armatures being so spaced apart that 60 each lies in one of said zones of high magnetic flux.

4. In a braiding machine of the class described comprising an outer rotary member and an inner rotary member, means for turning said outer and 65 inner members in opposite directions, radially

spaced concentric guides carried by the outer rotary member, said guides having grooves defining annular paths for the outer and inner ends, respectively, of a bobbin carrier, a bobbin carrier having its ends disposed in the respective grooves, and means for driving the bobbin carrier, said driving means comprising a permanent magnet mounted on the inner rotary member, and a series of spaced armature bars fixed to the carrier and extending in a substantially radial direction, the permanent magnet having a pole piece which, in the direction of the carrier path, is substantially as wide as the carrier, said pole piece having a series of parallel ribs, in number equaling the number of armature bars, and so spaced that each rib registers with one of said bars.

5. In a braiding machine of the class described comprising an outer rotary member and an inner rotary member, means for turning said outer and inner members in opposite directions, radially spaced concentric guides carried by the outer rotary member, said guides having grooves defining annular paths for the outer and inner ends, respectively, of a bobbin carrier, a bobbin carrier having its ends disposed in the respective grooves, and means for driving the bobbin carrier, said driving means comprising a permanent magnet mounted on the inner rotary member, and a series of substantially parallel spaced armature bars, the carrier comprising a bottom plate in which said bars are embedded, the permanent magnet being of U-shape with its poles radially spaced, each pole being of a length, in the direction of rotation of the carrier, substantially equaling the circumferential width of the carrier, the outermost of the armature bars being spaced from each other a distance substantially equaling the circumferential length of the magnet pole pieces.

6. In a braiding machine of the class described comprising an outer rotary member and an inner rotary member, means for turning said outer and inner members in opposite directions, radially spaced concentric guides carried by the outer rotary member, said guides having grooves defining annular paths for the outer and inner ends, respectively, of a bobbin carrier, a bobbin carrier having its ends disposed in the respective grooves, and means for driving the bobbin carrier, said driving means comprising a permanent magnet mounted on the inner rotary member, and a series of spaced armature bars, the carrier comprising a bottom plate which underlies the bobbin and in which said bars are embedded, the permanent magnet having a pole piece which, in the direction of rotation of the carrier, substantially equals in length the circumferential width of the carrier, the pole piece having a series of spaced ribs in number equal to the number of armature bars, said ribs defining spaced zones of intense magnetic flux, each of the armature bars being located within one of said zones.

7. A braiding machine of the kind having a rotating annular member and a series of bobbin carriers mounted thereon, a second series of bobbin carriers, means guiding the carriers of the

latter series to move in a path concentric with said annular member, and magnetic means for moving the carriers of said second series along said path, said magnetic means comprising a series of vertically narrow, substantially parallel armature bars fixed to the lower part of each carrier, each series extending substantially from one radial edge of its carrier to the other, a permanent magnet cooperating with each series of armature bars, and means for moving the several magnets in a path concentric with said annular member, each magnet having a pole piece which, in the direction of travel of the carriers, substantially equals in length the circumferential width of the series of armature bars.

8. A braiding machine of the kind having a braiding die defining the braiding point, an annular rotary member concentric with the die, means for turning said member, a series of bobbin carriers mounted on the annular member, a pair of concentric guides fixed relatively to said annular member, said guides having opposed grooves, a second series of bobbin carriers, said latter carriers having parts engaging said grooves and being supported and guided solely by the latter, the innermost of said concentric guides being wholly to one side of the yarns leading from the carriers of the second series to the braiding point, means for guiding the yarns from each carrier of the first-named series alternately over and under successive carriers of the second series, and magnetic means for moving the carriers of the second series along their guides in a direction opposite to the movement of said annular member, said magnetic means comprising a series of spaced armature bars fixed to each carrier and disposed in a plane substantially perpendicular to the axis of the annular member and below the bobbins on the carriers, said series of armature bars extending substantially from one radial edge of the carrier to the other, a permanent magnet cooperating with each of said series of armature bars, and a rotating support for the magnet, each magnet having a pole piece which, in the direction of rotation of the carriers, is substantially equal to the width of the corresponding carrier, the pole piece of each magnet having a series of projecting ribs in number equal to the number of armature bars of the corresponding series, said ribs being so spaced from the plane of the armature bars that the latter lie within zones of intense magnetic flux emanating from said ribs.
